UNITED STATES PATENT OFFICE.

RICHARD VARLEY, OF ENGLEWOOD, NEW JERSEY, ASSIGNOR TO VARLEY DUPLEX MAGNET COMPANY, A CORPORATION OF NEW JERSEY.

LOCKOUT FOR AUTOMATIC STARTERS.

Original application filed September 18, 1919, Serial No. 324,450. Divided and this application filed December 26, 1919. Serial No. 347,411.

To all whom it may concern:

Be it known that I, RICHARD VARLEY, a citizen of the United States, residing at Englewood, in the county of Bergen and 5 State of New Jersey, have invented certain new and useful Improvements in Lockouts for Automatic Starters, of which the following is a full, clear, and exact description.

This application is divisional of my co-pending application Serial Number 324,450, filed September 18, 1919.

An object of my invention is to provide a simple and reliable device which will operate automatically to prevent the actuation 15 of the self starter of an automobile engine while the engine is running, and thus eliminate the possibility of damaging the starter. Very many of the starter constructions in common use are liable to be injured in one 20 way or another if they are actuated while the engine is running. Perhaps the type most susceptible to injury are those in which a starter pinion is shiftable into and out of engagement with a co-operative gear, such 25 as a gear on the fly wheel of the engine. If the engine does not make sufficient noise to apprise the operator with certainty that it is running, there is always the danger that he will actuate the starter under the mistaken 30 belief that the engine is not running, with the resultant liability of stripping the teeth on the pinion, or otherwise injuring the mechanism.

In accordance with my invention I provide 35 an actuating member operatively connected to an engine driven shaft and arranged to be moved in the proper direction by the shaft and actuate a detent against its bias into locking relation to the manually 40 operated starter lever. Usually this lever will serve to shift the starter pinion and will be locked by the detent in the position in which the pinion is out of engagement with its co-operating gear wheel.

45 I shall now describe the illustrated embodiment of my invention and shall thereafter point out my invention in claims.

Fig. 1 is a plan of the automatic lock-out mechanism with a portion of the starter 50 mechanism shown in elevation in operative relation thereto;

Fig. 2 is a sectional elevation of the automatic lock-out mechanism.

In the construction shown the starter pin-

ion 1 is splined to the shaft 2 of the starter 55 motor 3 and is shiftable into and out of engagement with the gear teeth on the fly-wheel 4 by a reciprocable rod or lever 5. This rod has proper operative connection with the pinion 1 to effect the shifting movement, and for the purpose of illustration it is shown as provided with a depending fork or stirrup 6 which straddles a grooved collar on the end of the pinion 1. One end of the rod 5 is operatively connected to a suitable bell crank 7 shown as pivoted on the under side of the foot-board of the vehicle and provided with an operating extension through the foot-board terminating in a 60 pedal 8. The other end of the rod 5 is 70 pivotally connected to a pivoted member 9 which I term the locking member and which carries a knife contact 10 co-operative with the two stationary starter contacts 11. A retractile spring 12 tends to hold the above 75 described parts in the position shown with the pinion out of engagement with the gear teeth on the fly-wheel. To lock the member 9 and consequently the entire starter mechanism in the position shown when the engine 80 is running, suitable automatically operated detent mechanism is provided which will now be described.

In the form shown this mechanism is enclosed in a suitable housing 13 provided with 85 a horizontal wall or platform 14 on which the member 9 is pivoted. The member 9 is provided with an extension 9^a beyond the pivot and co-operative with this extension is 90 a detent 15 which is also pivoted in a suitable bearing in the wall 14 and which is provided with a nose arranged to be moved into and out of the path of the extension 9^a as the detent 15 is rotated on its pivot. A retractile spring 16 tends to hold the detent 95 15 against a stop 15^a with the nose out of the path of the extension 9^a.

To actuate the detent 15 against its bias into the path of the extension 9^a, suitable transmitting means are provided having operative connection with an engine-driven shaft 17. For the purpose of illustration I have chosen a transmission device of the type shown and described in my co-pending application, Serial No. 314,643, although it 100 will be understood that any suitable mechanism actuated by the shaft 17 may be employed for this purpose.

In the illustrated construction the primary member of the transmission comprises an annular cup-shaped member 18 secured axially upon the shaft 17 immediately above a suitable anti-friction bearing for the shaft 17 formed in the wall 14. The secondary member 19 rests on top of the primary member and is an annulus provided at its inner edge with a hub portion which loosely surrounds the center portion of the primary member, and therefore is free to turn thereon. A suitable cover 20 encloses the device.

The primary member 18 is provided with a plurality of concentric flanges 18^a intermediate of which are similar depending flanges 19^a on the secondary member. The device is partially filled with oil or other liquid which serves to couple the two members and transmit a torque to the secondary member. The secondary member carries an abutment 21 in position to engage the end of the pivoted detent 15 opposite the nose portion. Since the shaft 17 is driven in a clockwise direction as viewed in Fig. 1, it follows that the drag of the primary member upon the secondary member will cause the latter to rotate in a clockwise direction when the engine is running, and the abutment 21 will thereby actuate the detent 15 against the tension of the spring 16 and move the nose down into the path of the extension 9^a. The starter mechanism is thereby locked against actuation so long as the engine is running.

It is obvious that various modifications may be made in the construction shown in the drawings and above particularly described within the principle and scope of my invention.

I claim:

1. For an internal combustion engine including an automatic starter, an operating lever for the starter, a lock-out for the lever movable into and out of the path of the lever, a shaft connected to be rotated by the engine, and means mechanically connecting the shaft to the lock-out and operative by any rotation thereof to shift the lock-out to locking position.

2. For an internal combustion engine including an automatic starter, an operating lever for the starter, a lock-out for the lever movable into and out of the path of the lever and having a bias to non-locking position, a part mechanically movable by any rotation of the engine, and lock-out actuating means carried thereby.

3. For an internal combustion engine including an automatic starter, an operating lever for the starter, a lock-out for the lever movable into and out of the path of the lever and having a bias to non-locking position, a rotatable part angularly movable by the ro-

tation of the engine, and an abutment on the rotatable part adapted to engage and 65 actuate the lock-out against its bias.

4. For an internal combustion engine including an automatic starter, an operating lever for the starter, a lock-out for the lever movable into and out of the path of the lever 70 and having a bias to non-locking position, an engine driven shaft, a rotative primary member carried by the shaft, and a rotative secondary member arranged to have a drag imparted to it by the primary member and 75 operatively connected to the lock-out to move the same into the path of the lever.

5. For an internal combustion engine, in combination with a shiftable starter pinion and its cooperating gear, a reciprocating 80 lever operative to shift the pinion, a detent operative to engage and lock the lever with the pinion in disengaged position, and having a bias to non-locking position, a shaft connected to be rotated by the engine, and 85 a movable actuating device for the detent having mechanical connection with the shaft and movable by any rotation thereof to actuate the detent against its bias.

6. For an internal combustion engine, in 90 combination with a shiftable starter pinion and its cooperating gear, a reciprocating lever operative to shift the pinion, resilient retractile means tending to hold the lever in the disengaged position of the pinion, a 95 pivoted locking member operatively connected at one end to the lever, a pivoted detent movable into and out of the path of the locking member, resilient retractile means for the detent, an engine driven shaft, and 100 a movable actuating device for the detent having mechanical connection with the shaft and movable by any rotation thereof to actuate the detent into the path of the locking member.

7. For an internal combustion engine, in combination with a shiftable starter pinion and its cooperating gear, a reciprocating 110 lever operative to shift the pinion, resilient retractile means tending to hold the lever in the disengaged position of the pinion, a pivoted locking member operatively connected at one end to the lever, a pivoted detent movable into and out of the path of the locking member, resilient retractile means 115 for the detent, an engine driven shaft, a rotative primary member carried by the shaft, and a rotative secondary member arranged to have a drag imparted to it by the primary member and operatively connected 120 to the detent to move the detent into the path of the locking member.

In witness whereof, I hereunto subscribe my signature.

RICHARD VARLEY.
